Des. 216,061
Patented Nov. 18, 1969

216,061

PORTABLE ENCLOSURE FOR A TELEPHONE TRANSMITTER AND RECEIVER

Willard A. Hughes, Newhall, and Norman A. Kusche,
Glendale, Calif., assignors to American Systems, Inc.,
a corporation of California

Filed Feb. 17, 1969, Ser. No. 15,821

Term of patent 14 years

Int. Cl. D3—01; D14—03

U.S. Cl. D87—1

FIGURE 1 is a perspective view of the portable enclosure for a telephone transmitter and receiver in accordance with the present invention in the form of an attaché case illustrated with the cover closed;

FIGURE 2 is a perspective view thereof with the cover open; and

FIGURE 3 is a perspective view of an alternative embodiment thereof.

We claim:

The ornamental design for a portable enclosure for a telephone transmitter and receiver, as shown and described.
